BLOTTER HOLDER

Filed Jan. 7, 1933

INVENTOR
Hugh Whitt.
BY *Hugh Whitt.*
ATTORNEY.

UNITED STATES PATENT OFFICE

HUGH WHITT, OF FORTRESS MONROE, VIRGINIA

BLOTTER HOLDER

Application filed January 7, 1933. Serial No. 650,603.

(GRANTED UNDER THE ACT OF MARCH 3, 1883, AS AMENDED APRIL 30, 1928; 370 O. G. 757)

This invention described herein may be manufactured and used by or for the Government for governmental purposes, without the payment to me of any royalty thereon.

This invention relates to a blotter holder, and the primary subject thereof is to provide a device of this character which will automatically lift itself together with a blotter provided thereon after having been depressed for the purpose of blotting a signature or the like.

Another object of my invention is to provide a blotter holder comprising a frame having ends, a weighted portion provided on one of said ends, a slotted portion provided on another of said ends and a fulcrum support intermediate the ends of said frame.

Still another object of my invention is to provide a blotter holder which is simple and easy to operate, is not liable to get out of order and which may be manufactured at such low cost that it can be given away as an advertising medium.

With the above and other objects in view, the invention consists in the arrangement and combination of parts to be hereinafter more fully described and claimed and illustrated in the accompanying drawing, it being understood that various changes in form and other details may be resorted to without departing from the spirit or sacrificing any of the advantages of the invention.

Referring more particularly now to the accompanying drawing, in which corresponding parts are indicated by similar reference characters:

Fig. 1 is a side elevation of my invention in normal operative position having a blotter provided thereon;

Fig. 2 is a top plan view of my invention; Fig. 3 is a bottom plan view thereof;

Fig. 4 is a longitudinal sectional view taken on line 4—4 of Fig. 2, and

Fig. 5 is a cross-sectional view taken on line 5—5 of Fig. 3.

In the illustrative embodiment characterizing my invention A indicates generally my improved blotter holder which comprises a substantially rectangular frame 1 having rounded edges and made of any suitable ma-

terial preferably metal of sufficient thickness. The frame 1 is provided with a weighted portion 2 on the rear end 3 thereof and has a longitudinally extending horizontal slot 4 in the front end 5 thereof which provides an upper and lower part 6 and 7 respectively. The frame 1 is provided with a blotter 8 having one end 9 thereof slidably mounted in the slot 4. A rectangular cut-out portion 10 is provided in the upper part 6 which forms flanges or slide guide ways 11 on the upper part 6 along the longitudinal sides of the front end portion 5 and a transverse flange 12 on the rear end 13 thereof. The cut-out portion 10 also provides a window for viewing an advertising card 14 which may be slidably mounted on top of the end 9 of the blotter 8 within the slide guide ways 11 and flange 12. If desired the upper part 6 of the front end 5 of the frame 1 may be made solid and a suitable advertising medium may be provided on the upper surface thereof, such as by being stamped thereon or the like. In order to aid in guiding the end 9 of the blotter 8 and the advertising card 14 within the slide guide ways 11, the frame 1 may be provided with guide projections 15 at each side thereof at its front end. The guide projections 15 may be connected to the frame 1 in any suitable manner such as by being soldered thereto or may be made integral therewith as shown. Transversely mounted on the lower surface of the frame 1 and intermediate the ends thereof are substantially semi-circular lug members 16 which provide a fulcrum support 16' for the holder. The lug-members 16 may be connected to the frame 1 in any suitable manner such as by being welded thereto, or may be made integral therewith as illustrated in Fig. 5 of the drawing. The lug-members 16 are also so spaced from the rear end 3 of the frame 1 as to cause the weighted portion 2 provided thereon to pull the rear end 3 downward after the holder has been depressed for blotting a signature or the like, until the outer edge thereof rests on the top 17 of a desk or the like in alignment with the lower edge of the semi-circular lug members 16 or fulcrum support 16' thereby nor-

mally causing the frame 1 together with the blotter 8 which may be provided on the front end portion 5 thereof to assume a slanting position as shown in Fig. 1 of the drawing. 5 The holder is so constructed as to cause the frame 1 and blotter 8 to preferably assume an angle of substantially 12° with the top 17 of the desk. If desired the semi-circular lug-members 16 may be provided with apertures 18 for pivotally mounting the holder on any suitable support.

In operation my device functions as follows: Assuming that the blotter holder has been provided with a blotter and moved to 15 any suitable place on the top of a desk for blotting a signature or the like, the user thereof, presses downwardly with either his right or left hand on the front end of the holder or on the free end of the blotter 8, 20 this movement causes the right hand portion of the outer periphery of the semi-circular lug members 16 to frictionally engage the top of the desk in a counter clockwise direction which raises the weighted portion 2 on the 25 rear end 3 of the frame 1 upwardly until the blotter 8 has come into contact with the signature or the like to be blotted. When the holder is released the weighted rear end portion 2 thereof causes the left hand portion 30 of the outer periphery of the semi-circular lug members 19 to frictionally engage the top 17 of the desk in a clockwise direction until the lower edge of the weighted portion 2 rests on the top of the desk after 35 which the device is again ready for instant use.

It will thus be seen that I have provided a highly novel and efficient form of blotter holder which is well adapted for all the purposes designated. Even though I have herein described my invention as comprising certain structural features it is nevertheless to be understood that changes can be made therein without departing from the spirit or 45 scope of my invention.

Having described my invention what I claim as new and wish to secure by Letters Patent is:

1. A blotter holder comprising a frame 50 having ends, a weighted portion provided on one of said ends, a slot provided in another of said ends and a fulcrum support intermediate said ends.

2. A blotter holder comprising a frame 55 having ends, a weighted portion provided on one of said ends, a slot providing an upper and lower part in another of said ends, a cut-out portion provided in said upper part and a fulcrum support intermediate the ends of said frame.

3. A blotter holder comprising a frame having a front and rear end portion, a longitudinal horizontal slot in said front end portion, a weighted portion provided on the 60 said rear end portion of said frame and a

fulcrum support on the front end portion of said frame.

4. A blotter holder comprising a frame having ends, a weighted portion provided on one of said ends, a slot provided in another of said ends and a fulcrum support intermediate said ends, said fulcrum support comprising semi-circular lug members. 70

5. A blotter holder comprising a frame having ends, a weighted portion provided on one of said ends, a slot provided in another of said ends and a fulcrum support intermediate said ends, said fulcrum support comprising semi-circular lug members transversely mounted on said frame. 75

6. A blotter holder comprising a frame having a front and rear end portion, a longitudinally extending horizontal slot provided in said front end portion, an upper and lower part provided by said slot, a cut-out portion provided in said upper part, a weighted portion provided on the rear end portion of said frame and a fulcrum support on the said lower part of said front end portion. 80

7. A blotter holder comprising a frame having a front and rear end portion, a longitudinally extending horizontal slot providing an upper and lower part in said front end portion, a cut-out portion on said upper part providing slide guide ways, a weighted portion provided on said rear end portion of said frame and a fulcrum support on the lower surface thereof. 85

8. A blotter holder comprising a frame having a front and rear end portion, a longitudinally extending horizontal slot providing an upper and lower part in said front end portion, a substantially rectangular cut-out portion provided in the upper part of said slot, said cut-out portion providing slide guide ways on longitudinal side edges of said upper part and a transverse flange on the rear thereof and a fulcrum support on the lower surface of said frame. 100

9. A blotter holder comprising a frame having a front and rear end portion, said front end portion having a longitudinally extending horizontal slot provided therein, said slot providing an upper and lower part, a cut-out portion provided in said upper part, said cut-out portion forming a longitudinal slide guide way on opposite sides of said upper part and a transverse flange on the rear thereof, a weighted portion on the said rear end portion of said frame and a fulcrum support on the lower surface thereof, said fulcrum support comprising substantially semi-circular lug members. 105

10. A blotter holder comprising a frame having ends, a weighted portion provided on one of said ends and a fulcrum support intermediate said ends. 110
